US0D1053034S

(12) **United States Design Patent** (10) Patent No.: **US D1,053,034 S**
(45) Date of Patent: ** Dec. 3, 2024

(54) **WEIGHING APPARATUS**

(71) Applicants: **Mettler-Toledo (Changzhou) Measurement Technology Co., Ltd., Changzhou (CN); Metter-Toledo (Changzhou) Precision Instruments Ltd., Changzhou (CN); Mettler-Toledo International Trading (Shanghai) Co., Ltd., Shanghai (CN)**

(72) Inventors: **Youyi Wu, Greifensee (CH); Chunhui Li, Greifensee (CH); Zhihe Chao, Greifensee (CH); JinJie Cai, Greifensee (CH); Zheng Guo, Greifensee (CH)**

(73) Assignees: **Mettler-Toledo (Changzhou) Measurement Technology Co., Ltd., Changzhou (CN); Mettler-Toledo (Changzhou) Precision Instruments Ltd., Changzhou (CN); Mettler-Toledo International Trading (Shanghai) Co., Ltd., Changzhou (CN)**

(**) Term: **15 Years**

(21) Appl. No.: **29/884,207**

(22) Filed: **Feb. 8, 2023**

(30) **Foreign Application Priority Data**

CLAIM

The ornamental design for a weighing apparatus, as shown and described.

DESCRIPTION

FIG. 1 is a front perspective view of a weighing apparatus of our new design;

FIG. 2 is a bottom view thereof;

FIG. 3 is a left side view thereof;

FIG. 4 is a front view thereof;

FIG. 5 is a top view thereof;

FIG. 6 is a rear view thereof;

FIG. 7 is a right side view thereof; and,

FIG. 8 is a rear perspective view thereof.
